CLINTON F. WAIT, OF PINE BLUFF, ARKANSAS

LEVEE MACHINE

Application filed November 9, 1931. Serial No. 573,991.

My invention relates to improvements in levee machines of the tower dragline type, and it consists in the combinations, constructions, and arrangements herein described and 5 claimed.

An object of my invention is to provide a novel sled type bucket which may be tilted and otherwise operated by remote control.

10 A further object is to provide novel means in a device of the type described which will prevent the bucket from capsizing when in operation.

15 A further object is to provide novel means for holding the actuating lines out of engagement with the ground.

20 Other objects and advantages will appear in the following specification, and the novel features of the invention will be particularly pointed out in the appended claims.

25 My invention is illustrated in the accompanying drawings, forming part of this application, in which

Figure 1 is an elevational view of my invention as used in constructing levees,

25 Figure 2 is an elevational view of my invention as in operation,

Figure 3 is an elevational view showing the bucket and its associated mechanism during the digging operation,

30 Figure 4 is a perspective view of the bucket and associated mechanism, and

Figure 5 is an elevational view showing the bucket and associated mechanism subsequent to the digging operation.

35 In carrying out my invention, I provide an operating tower or derrick 1 and an anchor tower 2. The anchor tower 2 is normally positioned at a distance from the actuating tower 1. Both of said towers are, however, transportable by reason of the fact that they may be mounted on any suitable transporting means such as Caterpillar tracks 3. The operating tower 1 is of much greater height than the anchor tower 2 for the reasons hereinabove described and is positioned adjacent the location where the levee is to be built. The tower 1 is provided with a housing 4 in which an operating mechanism or machinery is disposed. A supporting line or cable 5 is operatively associated with the operating

mechanism in the housing 4 and extends over a wheel 6 mounted on the top of the operating tower 1 from whence it extends to the anchor tower 2. The supporting line 5 extends over a wheel 7 rotatably mounted on the anchor 55 tower 2 and is operatively connected with machinery disposed within the housing 8 of said anchor tower.

As shown in Figure 4 I further provide a bucket or receptacle 9 having an end wall 60 10, side walls 11, and a bottom wall 12. The top and an end of the receptacle are open as shown in Figure 4. The bottom wall 12 is provided with a projecting portion 13 which is positioned at an angle with respect to said 65 bottom wall. The side walls 11 are also provided with projecting portions 14 which are connected with the projecting portion 13 and serve as means for reinforcing the same. The projecting portion 13 functions as a scoop or 70 shovel as will be hereinafter described. Each of the side walls 11 is provided with a lug 15 fixedly connected therewith and a projecting lug or flange portion 16 connected with the top edge thereof. A carriage 17 is movably 75 mounted on the supporting line 5 by means of wheels 18 mounted on the carriage and traveling on the supporting line 5.

A supporting chain or link means 19 is pivotally connected with the carriage 17 by 80 means of a pin 20 and is connected with a pair of diverging link portions 21 which in turn are connected with the lugs 15. A spacing member 22 is disposed between the diverging members 21 for holding the same in 85 a definite spaced-apart relationship. An actuating line or cable 23 has one end pivotally connected with the carriage 17 by means of a pin 24 and extends over a wheel or pulley 25 rotatably mounted on the operating tower 90 1 from which it extends to a rotatable drum 26 on which it is wound, said drum being carried by the operating tower and operatively associated with the operating mechanism disposed within the housing 4. A spacer trolley 27 comprises a pair of spaced-apart wheel carrying elements 28 and 29 on which are respectively mounted wheels 30 and 31. The wheel 30 travels on the supporting line 5 and the wheel 31 travels on the actuating cable 23. 100

The wheels 30 and 31 are held in their spaced-apart positions by means of a spacing member 32 connected with the wheel carrying elements 28 and 29.

5 A depending link means 33 has one end pivotally connected with the wheel carrying element 29 and the other end connected with a connecting member 34. A draft line or pulling cable 35 has one end connected with the 10 connecting member 34 and extends over a pulley wheel 36 mounted on the derrick 1. The draft line cable is wound on a drum 37 rotatably mounted on the derrick 1 and operatively associated with the mechanism disposed within the housing 4. A pair of draft members or link elements 38 is provided for connecting the flange members 39 mounted on the receptacle 9 with the connecting member 34.

20 A pair of telescoping arms 40 is connected with the opposite sides 11 of the bucket 9 and the respective draft members 38. Each arm 40 comprises a female arm portion 41 having an end connected with a side of the casing 25 and a male arm portion 42 having an end connected with a draft member 38. The male arm portion is slidably disposed in the female arm portion and is provided with a lug 43 extending through a slot 44 in the female member for limiting the movement of said male arm portion relative to the female arm portion.

30 A cable supporting trolley 45 is provided comprising a supporting member 46 and a supported member 47. A tie member 48 is provided for connecting the supported member with the supporting member. A supporting wheel 48' is rotatably mounted on the supporting member 46 and travels on the 35 supporting cable 5.

40 Spaced-apart supported wheels 49 and 50 are rotatably mounted on the supported member 47 and are adapted for respectively supporting the actuating cable and the landing cable beneath which said wheels are positioned. A tie or anchor line 51 is connected with the cable supporting trolley 45 and the operating tower 1. The cable supporting trolley may be anchored to the tower at any 45 suitable distance therefrom. A number of these cable supporting trolleys may be utilized depending on the length of span of the supporting line 5.

50 From the foregoing description of the various parts of the device, the operation thereof may be readily understood.

When it is desired that dirt be piled up for constructing a levee the operating tower is first positioned adjacent the location where the 60 dirt is to be piled and the anchor tower is positioned at a distance therefrom. The bucket 9 is first positioned adjacent the anchor tower 2 and the tension on the supporting line 5 is released whereby the bucket 65 may be disposed on the surface of the ground,

at which time the bucket will be in the position shown in Figures 2, 4, and 5. The drum 26 is then rotated sufficiently for exerting enough tension on the actuating line 23 for moving the trolley carriage 17 to the position shown in Figure 3 relative to the bucket 9. When the trolley carriage 17 is moved to the position shown in Figure 3, the spacing member 22 engages the lugs 16 of the bucket thereby tilting the bucket to the position shown in Figure 3, at which time the scoop or shovel portion 52 of the bucket will be in its digging position with respect to the ground. The drums 26 and 37 are then rotated at the same rate of speed, provided that they are of the same size, so that the carriage 17 and the bucket 9 move at the same rate of speed thereby holding the bucket in its tilted position and causing the same to be filled with the material which it scoops from the ground. When the bucket has been pulled along the ground a sufficient distance to enable it to become filled with material, the tension on the actuating line 23 is temporarily released, at which time the bucket assumes the position with respect to the trolley carriage 17 as shown in Figures 2, 4, and 5, whereby the shovel portion 52 will be moved out of engagement with the ground so that as the bucket member continues its movement along the ground it will not continue to load itself with material.

55 The bucket is of the sled-runner type in that the cutting edge of the scoop portion is positioned above the bottom of the bucket. When the bucket is pulled to the position where it is desired that the load be dumped power is applied to the supporting line 5 for tensioning the same whereby the bucket may be lifted from the ground. The tension on the actuating line 23 and the draft line 35 is then released whereby the bucket may drop to the position 9a for dumping its load as shown in Figure 2. It will also be noted that the track line 5, when in tension, is positioned at 5a. It will also be noted that when the track line 5 is under tension that the cable supporting trolley 45 is positioned at 45a. Thus it will be seen that the cable trolley 45, together with the spacer trolley 27, serves to keep the actuating and draft cables, together with the draft members 38, out of engagement with the ground regardless of the position of said bucket. When the bucket has dumped its load the drums 26 and 37 are rotated for slackening the actuating cable 23 and the draft cable 35 for permitting the bucket to travel by gravity back to the locality of the anchor tower where it is again positioned for loading. It will be 100 seen that when the bucket is being loaded the telescopic arms 40, by reason of their being connected with the bucket and the taut draft members 38, will prevent the bucket 105 from overturning even though the shovel portion 95 110 115 120 125 130 135 140 145 150 155 160 165 170 175 180 185 190 195 200 205 210 215 220 225 230 235 240 245 250 255 260 265 270 275 280 285 290 295 tion 52 thereof should engage an obstacle such as a large rock. The telescopic arms also aid in positioning the bucket at the proper angle with respect to the ground for 5 the digging operation.

The arms 40 permit the bucket to be manipulated without hindrance.

I claim:

1. In an excavating apparatus, the combination of a pair of spaced apart elevated supports, a power means associated with one of the supports, a supporting line extending between the supports and operatively associated with the power means, a carriage mov- 15 ably carried by the supporting line, a carriage drawline connected with the carriage and operatively associated with the power means, a bucket, a suspension means for mov- ably connecting the bucket with the carriage, 20 draw means connected with an end of the bucket, a dragline connected with the draw means and operatively associated with the power means, and a spacing trolley connected with the draw means and operatively associated 25 with the supporting line and carriage drawline for holding said lines in spaced apart relationship.

2. In an excavating apparatus, the combination of a pair of spaced apart elevated supports, a power means associated with one of the supports, a supporting line extending between the supports and operatively associated with the power means, a carriage mov- 30 ably carried by the supporting line, a carriage drawline connected with the carriage and operatively associated with the power means, a bucket, a suspension means for mov- ably connecting the bucket with the carriage, 35 draw means connected with an end of the bucket, a dragline connected with the draw means and operatively associated with the power means, a spacing trolley connected with the draw means and operatively associated with the supporting line and carriage drawline for holding said lines in spaced apart relationship, an auxiliary trolley mov- 40 ably suspended from the supporting line, and a tie line connecting the auxiliary trolley with one of the elevated supports, said auxiliary trolley being operatively associated with 45 the carriage drawline and the dragline for supporting the same in spaced apart positions.

3. In an excavating apparatus, the combination of a carriage, a bucket, a pair of spaced apart suspension means connected with the carriage and opposed sides of the bucket, a pair of spaced apart draw means connected with the opposed sides of the buck- 50 et and connected with a dragline, a pair of telescopic arms connected with each of the opposed sides of the bucket and the draw means, each of said telescopic arms comprising a female arm portion and a male arm portion, one of said arm portions being mov- 55

ably connected with the bucket and the other of said arm portions being movably connected with the draw means, and means connected with one of the arm portions for limiting the movements thereof with respect to 70 the other arm portion.

4. In an excavating apparatus, the combination of a carriage, a bucket, a pair of spaced apart suspension means connected with the carriage and opposed sides of the bucket, a pair of spaced apart draw means connected with the opposed sides of the bucket and connected with a dragline, a pair of telescopic arms connected with each of the opposed sides of the bucket and the draw means, each of said telescopic arms comprising a female arm portion and a male arm portion, one of said arm portions being movably connected with the bucket and the other of 75 said arm portions being movably connected with the draw means, and means connected with one of the arm portions for limiting the movements thereof with respect to the other arm portion, said bucket being provided with upwardly extending lug portions 80 and a cross bar member positioned between and connected with the suspension means and adapted for engagement with the lug portions.

5. In an excavating apparatus, the combination of a carriage, a bucket, a pair of spaced apart suspension means connected with the carriage and opposed sides of the bucket, a pair of spaced apart draw means connected with the opposed sides of the bucket and connected with a dragline, a pair of telescopic arms connected with each of the opposed sides of the bucket and the draw means, each of said telescopic arms comprising a female arm portion and a male arm portion, one of said arm portions being movably connected with the bucket and the other of said arm portions being movably connected with the draw means, one of said arm portions being provided with a slotted opening 90 therein, and a pin fixedly connected with the other arm portion and extending through the opening for limiting the movement of said arm portion with respect to the other arm portion.

6. In an excavating apparatus, the combination of a bucket, draw means connected with the bucket, an arm connected with the bucket and the draw means and comprising a pair of arm portions slidably longitudinally with respect to each other, one of said arm portions being connected with the bucket and the other of said arm portions being connected with the draw means, and means associated with the arm portions for limiting the longitudinal movements thereof with respect to each other.

7. In an excavating apparatus, the combination of a carriage, a bucket, a pair of 130

spaced-apart suspension means connected with the carriage and opposed sides of the bucket, said bucket having said opposed sides provided with lug portions, and a spacing member positioned between and connected with the suspension means and adapted for engaging the lug portions when the bucket is disposed in certain positions with respect to the carriage.

10. 8. In an excavating apparatus, the combination of a pair of spaced apart elevated supports, a power means associated with one of the supports, a supporting line extending between the supports and operatively associated with the power means, a carriage movably carried by the supporting line, a carriage drawline connected with the carriage and operatively associated with the power means, a bucket, a suspension means for movably connecting the bucket with the carriage, draw means connected with an end of the bucket, a dragline connected with the draw means and operatively associated with the power means, a spacing trolley suspended from the supporting line and connected with one of the elevated supports, said trolley being operatively associated with the carriage drawline and the dragline for supporting the same in spaced apart positions.
